UNITED STATES PATENT OFFICE.

ALBERTUS B. MATTINGLY, OF NEW YORK, N. Y.

ATTACHMENT FOR SEWING MACHINES.

Application filed January 21, 1920. Serial No. 352,980.

To all whom it may concern:

Be it known that I, ALBERTUS B. MATTINGLY, a citizen of the United States, and resident of New York, in the county of New York and State of New York, have invented certain new and useful Improvements in Attachments for Sewing Machines, of which the following is a specification.

This invention relates to an improvement in attachments for sewing machines, and the inventor is aware that the device is of a nature similar to that disclosed in British Letters Patent No. 17,153 of 1905, to Hills, and United States Patents No. 412,081, to Fletcher, No. 446,736, to Fletcher, No. 990,601, to Seward, and No. 990,610 to Turck, and the object is to overcome some of the objectionable features of these devices and to further improve the same.

The principal objects are to provide a device of this character to automatically cut or slit the cloth just in advance of the stitching or binding of the button-hole so that the needle may pass alternately through the cloth and then through the slit or cut, thus causing the thread to be brought through the cut and make a perfect binding of the raw edges of the work, and to provide a means for positively actuating the knife with a quick and decisive action at the proper periods to make the cut the proper length according to the length of the button-holes, and to have the length of cut automatically adjust itself with the adjusting of the device for the length of the button-hole.

The further objects are to provide a device of this character which will provide a means for more evenly distributing the stitches around the contour of the button-hole than has heretofore been accomplished, and to provide a means whereby a more perfect adjustment of the cutting device as regards its alignment relative to the needle of the sewing machine is obtained.

The still further objects are to provide a device of this character which by its construction is considerably reduced in height and thereby doing away with the necessity of removing the face plate of the sewing machine to adjust the presser bar, and by the construction of the base plate obviating the necessity of removing the feed dogs of the sewing machine.

The still further objects are to provide an improved ratchet device for effecting the

lateral vibration of the work clamp, to produce the overstitch of the edge of the button-hole, and to form other parts of the device by the stamping process, screw machines, which is the cheapest method of manufacturing devices of this class.

A still further object is to provide a device of this kind in which the knife can be adjusted to cut a line or slit in which the needle will follow with its inside lines of its vibrating motion on its forward movement and also perform the same function on its backward movement in forming or stitching the button-hole.

With these and other objects in view, it will be seen that I accomplish the foregoing, by referring to the accompanying drawings forming a part of this specification; but I do not wish to confine myself to the exact construction shown, as I have, for the sake of clear illustration, exaggerated some of the parts, especially in the side elevations, and the cam faces of the yoke upon which the eccentric cam works.

In the accompanying drawings, showing one embodiment of my invention, Figure 1 is a plan view of the device; Fig. 2 is a similar view to Fig. 1, partly broken away to show the revolving disk and the cam for moving the work clamp; Fig. 3 is a similar view to Fig. 2, with the revolving disk removed; Fig. 4 is a similar view to Fig. 3 and a section taken on line 4—4 of Fig. 5; Fig. 5 is a side elevation; Fig. 6 is a sectional view taken on the line 6—6 of Fig. 5; Fig. 7 is a similar view to Fig. 6, with the knife and its operating means removed; Fig. 8 is a similar view to Fig. 7, with the work clamp removed showing the vibrating means; Fig. 9 is a similar view to Fig. 8, with the vibrating means removed; Fig. 10 is a central vertical sectional view; Fig. 11 is a perspective view of the operating lever; Fig. 12 is a detail plan of the vibrator; Fig. 13 is an end elevation of the vibrator; Fig. 14 is a side elevation of the vibrator; Fig. 15 is a perspective view of the vibrator carrier; Fig. 16 is a plan of the supporting plate; Fig. 17 is a bottom plan of the revolving disk; Fig. 18 is a central section of the revolving disk; Fig. 19 is a plan of the camming plate; Fig. 20 is a side elevation of the camming plate; Fig. 21 is a plan of the knife carrier; Fig. 22 is a side elevation of the knife carrier; Fig. 23 is a plan of

the knife shield and integral therewith the stripper plate for the needle and the guide for the work clamp; Fig. 24 is a side elevation of Fig. 23; Fig. 25 is a plan of the work clamp; Fig. 26 is a plan of the ratchet cam; Fig. 27 is a section of the ratchet cam; Fig. 28 is a plan of the pawl plate of the vibrator; Fig. 29 is a plan of the spring pawl for operating the ratchet cam; Fig. 30 is a bottom plan of the cam member showing the cam for operating the knife and the race cam for controlling the work clamp; Fig. 31 is a plan of the upper portion of the assembling stud carrying the brake springs; Fig. 32 is a side elevation of Fig. 31; Fig. 33 is a plan of the lower portion of the assembling stud and Fig. 34 is a side elevation of Fig. 33; Fig. 35 is a plan of the linkage for alining the work clamp 20 and knife with the needle; Fig. 36 is a diagrammatic view showing the movement of the work clamp and cam when the operating cam moves in a circular motion; Fig. 37 is a view similar to Fig. 36, but showing the cam moving in an elliptical path; Fig. 38 is an enlarged transverse sectional view taken through the work clamp on line 2—2, Fig. 2; Fig. 39 is an enlarged central sectional view of the lower stripper plate; Fig. 40 is an enlarged perspective view of the stripper plate.

I provide a suitable base plate 1, which is secured to a rear throat plate 2 of the sewing machine in any suitable manner, but preferably screwed thereto, as shown in Fig. 1 of the drawings.

The base plate 1 is provided with an ear 3, which is upwardly turned and carries the operating lever 4, which rocks on a pivot 5 formed of a large screw, the lever 4 being provided with a bifurcated end 6, which engages the shank of the screw of the tightening collar of the needle bar of the sewing machine. The lever 4 is further provided with an arc-shaped slot 7 through which passes the arm of the friction clutch, which receives its movement from the screw 8 in the ear 9 and the rear end 10 of the slot 7. The screw 8 is frictionally held from turning by the pressure of the spring 11 against its head and the ear 9. The lever 4 is further provided with an arm or downward extension which has a bifurcated end 12 which operates the pawl 13 and the pawl plate 14 by the lever 15, which is mounted on the throat plate 2 by means of a body screw forming a pivot 16. In the forward end of the lever 15 is a pin 17 (see Figs. 9, 28 and 29) which operates the pawl 13 and the pawl plate 14 through the slots 18 and 19.

The base plate 1 is further provided with a pivot or stud 20 made up of two parts 21 and 22. The lower portion 21 of the stud is hollow and has its upper and lower ends

turned down, leaving a body portion 23 which is slotted on opposite sides forming grooves 24 for the reception of the extensions 25 of the part 22, and a washer 26 is forced on to the lower part of the part 21. The washer 26 forms a substantial base for holding the stud in a vertical position on the base plate, which is done by the screw 27 passing through the washer and the base plate 1 and the hollow part 21 and being screwed into the part 22, which locks all of the several parts assembled on the stud in position by its head 28, in which are secured two springs 29 which act as friction brakes in connection with the cam member 30, which is driven by a friction device (see Figs. 4 and 10) composed of a friction ring 31 supported by a flange 32 on the cam member 30; in the recess 33 of the ring is pivoted a friction dog 34, which is normally held in contact with cam member 30 by a spring 35. The lever 36 of the dog passes through an opening or slot 7 in the operating lever 4 and is operated by the screw and the rear end of the slot 7, the screw 8 forcing the dog and ring backwards and relieving the pressure on the cam member. The springs 29 bearing against the surface 37 prevent the cam member from turning, and the rear end of the slot forces the dog forward and causes the nose 38 to bite or grip the surface 39 of the cam member 30 and revolve the same a predetermined amount, which is regulated by the screw 8. The plate 40 fixed on the upper face of cam 30 keeps the ring in position.

Rotatably mounted upon the stud 20 and supported by the washer 26 are the pawl 13 and the pawl plate 14 (which are swung in an arc by the end 12 of the lever 4 through the lever 15 and its pin 17, in a forward and backward movement). Rotatably mounted upon the stud 20 and resting upon the pawl plate 14 is a ratchet cam 41, which receives a step by step rotary movement from the upturned end 138 of pawl 13 extending through a slot in plate 14 and engaging in turn the notches 137 of ratchet cam 41, and which operates the vibrator 56, which has its support on the pawl plate and is pivoted on the pin 51 of the L-shaped member 52.

The base plate 1 is further provided with a cut-away portion 43 in which is located a linked member 44 having a slot 45 and a circular opening 46 which fits the head of the screw 27 which acts as a pivot. Secured to the forward end of the linked member 44 by a pivot is a link 47 with an upturned end 48, which is tapped for the screw 49 which passes through a hole in the ear 3 and is provided with a lock nut 50. By turning the screw 49 to pull or push the link 47, the slot 45 can be made to line up perfectly with the needle and the stud 20 and held in this po-

sition by the lock nut 50. The slot 45 is for receiving the bottom end of the pin 51 of the L-shaped member 52, which is provided with a slot 53 for adjusting it upon the base plate 1 by the screw 54, and it is provided with an upturned ear 55 for adjusting it while the screw 54 is loose. The pin 51 is tight in the member 52 and its upper end forms a pivot for the vibrator 56, which is connected thereto by the hole 57 in the ear 58, and when assembled the ear 58 is capable of passing under the pawl 13 and pawl plate 14, while the yoke 59 straddles the ratchet cam and rests upon the pawl plate 14. The L-shaped member 52 is to regulate the width of bite of the overstitch which is made by the throw or transverse movement of the work clamp, by moving the member 52 so that the pin 51 is moved to and from the stud 20. The nearer the pin 51 is to the stud 20 the greater the transverse movement of the work clamp.

The vibrator 56 is provided with a pivoted block 60 which fits the inner faces of the rear yoke 62 of the work clamp 63, which straddles the stud 20 and rests on the supporting plate 61, which, working in conjunction with the cam member 30, keeps the forward part 64 of the work clamp in proper contact with the base plate 1 and prevents the bottom plate 65, which carries the stripper plate 160, from leaving the slotted way 66 in the base as it is oscillated by the work clamp in connection with the ears 67.

In order to insure a clean straight cut in the fabric in which a button-hole is to be worked, I provide a stripper plate 160 (see Figs. 38-40) which is pivoted at 161 to the plate 65 and is of a width equal to the inner side of the lower jaw of the work clamp which it fits, the sides 162 acting as guides on the inner side of the work clamp to always keep the T-shaped slot in perfect alignment with the knife, which is also guided by the inner surface of the work clamp, and this allows the surface 163 to act as a cutting edge for the knife and allows it to make a shearing cut instead of a puncture as was the case in the former patents cited. It is understood that the work clamp always oscillates in an arc controlled by the pin 80 and that the plate 65 oscillates in a straight line. Thus the T-shaped slot when in the plate 65 had to have the part 164 wide enough to prevent the knife from hitting it when the work clamp was at various angles to the plate, and therefore prevented a shearing cut.

The supporting plate 61 is held in position by resting on the shoulders 68 of the bottom part of the stud 21, which fits the hole 69 provided with slots through which pass the extensions 25 of the upper part 22 of the stud 20 and prevent it from turning and causing the springs 29 to act as friction

brakes on the cam member 30, for which the upper part acts as a journal. The screw 27 pulling down on the part 22 pinches the plate 61 between the shoulder 68 and the part 70 of the upper part 22 of the stud.

Mounted upon the yoke 62 is the guide or shield 71 for the knife carrier 72, having its front end 73 in the form of a stripping plate which slides in a groove or space 74 formed by a plate 75, which is forced into the upper jaw 76 of the work clamp. The groove 74 acts as a guide to keep the stripping plate 73 in line with the work clamp. The rear end of the shield 71 is enlarged, forming a guide 77, by means of the downwardly extending flanges 78 fitting the yoke 62, which moves back and forth relatively to the stud 20. The rectangular opening 79 is of a width equal to the diameter of the upper part 22 of the stud 20, which passes through it and prevents the shield from moving back and forth but allows its rear end to be drawn laterally of the stud 20 in both directions by the pin 80 working in the cam groove 81 formed by the cams 82 and 83 on the under face of the cam member 30 (thus causing the vibrator to vibrate or oscillate the work clamp in the contour of a button-hole while the revolving disk is moving the work clamp back and forth the length of the button-hole).

Mounted upon the guide or shield 77 is the knife carrier 72, which has its spring portion 84 passing through the openings 85 and 86 of the shield 71, which acts as guides for the carrier. The spring portion 84 has its outer end bent upward, with two ears 87 forming a pair of jaws for the knife 88, which is held by a pin or screw 89. The rear end of the spring portion 84 is formed in a rectangular frame or yoke 90 having a flange 91 forming a cam face 92 against which the cam 93 secured to the cam member 30, works, and the flexible portion 94 insures the keeping of the cam 93 and the cam face 92 always in contact. At a predetermined point the flange 91 forming the cam face 92 is cut away or ends at 95, and the yoke is so formed at this point as to have a clearance space 96 to prevent the yoke frame from hitting the cam 93 when the flexible part 94 of the yoke causes the yoke and knife to move quickly back between the strokes of the needle and thus prevent the needle bar from striking the knife several times while it is being moved back from under the needle bar. This quick movement is caused by the cam 93, which holds the yoke forward for the proper time, having an abrupt drop 97, so that while it is revolving on the stud 20 the point 98 passes the point 95 on the cam 92. The point 98 is so formed as to not interfere with the point 95, and this allows the yoke to move back its full stroke 130

at this point, which is accomplished on one of the upward strokes of the needle bar.

Mounted fixedly on the top of the stud 20 and held in place by dowel pins 99 is a camming plate 100, which works in conjunction with the driving plate 101 secured to the cam member 30 and which causes the revolving disk 102 to revolve in the path of an ellipse relative to the stud 20 and having its major axis in line with the work clamp and its minor axis transverse therewith and the intersection of its axes to the rear of the stud 20. The revolving of the disk in an elliptical path is caused by its pivot pin 103 shifting its position in the slot 104 as it revolves. The shifting of the pin is caused by the pivoted cam 105 sliding in the shallow slot 106. It will be noted that the slot 104 is deeper than the slot 106; this is to prevent the pin 103, from entering the slot 106 at the critical point when the disk 102 is being driven by the driving plate 101, which is connected to the disk 102 by the pivoted cam or block 107, which is free to slide in the slot 108 of the driving plate.

The foregoing movement will be more clearly understood by referring to Fig. 3, where I have indicated by dotted lines the positions of the pivoted cams and pins—and the starting position of the driving plate for each cycle. To make a button-hole, with the driving plate in the position indicated in dotted lines 109, the cam 107 will be at 110 and the pivot pin 103 at 111 and cam 105 at 112. When the driving plate reaches the position indicated at 113 the cam 107 will be at 114 and its center will represent the end of the minor radius of the ellipse and the cam 105 will be at 115 and the pivot pin 103 will be in the center of the camming plate. While the driving plate is moving to the position shown in full lines the pivot pin 103 moves along the slot 104 to 116 and the cam 105 returns to the center of the camming plate, and as the driving plate continues its circular movement to the position 109 the cam 105 moves over to 117 and back to the center of camming plate. Mounted upon the revolving disk is an adjustable cam 118 held in position by a stud 119 having a rectangular head 120 which fits the recess 121 and which guides it in its movement. The stud passes through a slot 122 and the cam into a screw cap 123, which causes the cam 118 to bind against the disk 102. This cam moves in an elliptical path, and the lengths of the axes are changed by the adjustment of the cam on the disk 102 relative to the pin 103. The cam 118 performs the function of the eccentric cam of the patents mentioned in this specification and produces a more satisfactory result.

The cam 118 moves the work clamp forward and back from the stud 20 and 65 in line with the needle through the yoke

member 124, which is secured to the work clamp and is provided with a slot 125 in which the cam 118 is located, and as the cam revolves it works against the face 126 first to drive the clamp forward and against the face 127 to draw the clamp back. The yoke member 124 is secured to the work clamp 63 by means of screws 128, and the forward end is bifurcated and bent so as to form bearings for the locking member 129, which is formed of a bent wire having a central portion 130 which acts in the capacity of a hand lever to operate the two end portions 131 which act upon the spring extensions 132 of the upper jaw 63 and which are riveted to the rear yoke 62 of the work clamp. 75

Mounted on the underside of the base plate 1 (see Figs. 8 and 9) is a spring member 133, which is held in position by the rivets 134 and has an upwardly extending portion 135 which extends through the opening 136 of the pawl plate 14 and into the holes 137 of the ratchet cam 41. This prevents the ratchet cam from being turned backwards by friction of the end 138 of the pawl slipping out of any one of the holes 137 upon its backward movement after it has revolved the ratchet cam one-tenth of a turn. 80

The base plate is further bent or formed so as to have a raised portion 139 through the center thereof, upon which the bottom of the work clamp slides and on which is cut the channel or groove 66 for the plate 65, on which is pivoted the stripper plate, 100 which has an opening 140 somewhat in the shape of a T. Beneath the stripper plate 160 in the base plate is an opening 141 and a similar one in the plate 65 to allow the needle to perform its functions. The raised portion 139 forms a channel or groove 142 (see Fig. 10), which allows the free action of the feed dogs of the sewing machine and raises the device enough to permit the cutting of the cloth without the knife hitting 110 the dogs on its downward stroke.

The operation of the device is very simple. The rear throat plate of the sewing machine is removed and the device is slipped in its place by the insertion of the throat plate 2 115 which is screwed to the device, and the shank of the screw which holds the needle in position passes into the bifurcated end 6 of the lever 4. When the attachment is first put on the machine the screw 54 and lock nut 50 are loosened and the screw 49 turned to bring the knife in line with the needle. The lock nut 50 is then tightened up. This holds the slot 45 in a perfect line with the needle and then the member 52 can be adjusted for any width of vibration for the work clamp. The screw 54 is then tightened and the attachment is ready for operation. It will be understood that after the knife has been once adjusted for the needle the 120 125 130

attachment can be removed if desired and put back without the knife being readjusted, and the vibrating movement of the work clamp can also be changed to take more or less bite when the attachment is adjusted to make a larger or smaller button-hole, without disturbing the adjustment of the knife.

To make a button-hole, the work clamp is set by operating the sewing machine until the extreme back position is reached. The lever 130 of the locking member 129 is then pressed forward, (that is, in the direction of the needle), and forces the ends 131 backwards and thus relieves the pressure of the springs 132, which allows the jaws of the work clamp to open. The cloth is inserted between the jaws and the lever 130 pushed back to its original position, thus causing the upper jaw to force the cloth down into the concave opening in the lower jaw, and at the same time the flanges 143 of the upper jaw prevent the slipping of the cloth on the lower jaw and thus causes the cloth to be stretched like a drum head. With the work clamp in this position the knife is in the dotted position shown in Fig. 5, and upon running the machine the needle bar strikes the top of the knife and forces it through the cloth each time the needle descends, making a shearing cut against the edge 163 of stripper plate 160, until the work clamp is almost at its extreme forward position, when the cam 93 is at the point where the point or nose 98 passes the point 95. The flexible portion 94 of the yoke causes the yoke to move swiftly back and draw the knife out of line with the needle bar before it has time to descend and strike it again, (as shown in full lines in Fig. 5), thus preventing further cutting, and the knife remains in this position until the button-hole is finished.

The stud 20 is the pivot center upon which the work clamp is oscillated by the vibrator 56. With each upward movement of the needle bar the lever 4 is raised, which in turn swings the pawl plate 14 sufficiently to have the pawl 138 act on one of the holes 137 of the ratchet cam and revolve it one-tenth of a revolution, which causes one of the pointed cam faces 143 to act on one side of the yoke 59 and cause the vibrator to swing to one side on its pivot 51. The face 144 prevents any overthrow of the vibrator. The next stroke of the needle causes one of the faces 143 to act on the opposite side of the yoke 59 and swing it in the opposite direction. This movement of the vibrator causes the work clamp to be oscillated on its pivot 20, such motion being transmitted through the block 60 of the vibrator. While the vibrator is oscillating the work clamp in one direction or the other with every stroke of the needle to make the needle pass first through the cloth and then through the cut, the elliptical cam is slowly shoving the

work clamp forward the length of the button-hole, the speed of the forward movement being regulated by the screw 8, which strikes the arm or lever 36 of the friction clutch and forces the ring 31 back a predetermined amount, (upon the downward stroke of the needle). The rear end 10 of the slot 7, upon reaching the arm 36, (on the upward movement of the needle) forces the ring to move forward and the nose 38 to bite into the cam member 30 and cause it and the revolving disk to revolve, which causes the cam 118 to act upon the face 126 of the yoke member 124 and shove the work clamp forward, and when the cam, on the last half of the revolution of the revolving disk, works against the face 127 it causes the work clamp to be drawn backwards. The revolving of the cam member 30 causes the pin 80 to shift its position while the button-hole is being made. This is due to the pin 80 being held relative to the stud 20 by the groove 81 and in the start is in the portion 145 which forms a part of the back end of the button-hole, that is, the part which is furthest from the edge of the garment. The part 146 holds the pin in a position so that the vibrator will vibrate the work clamp up one side of the slit which is being made by the knife for the button-hole. The part 147 then causes the pin 80 to move nearer to the stud 20, and this causes the first part of the loop or eyelet to be made, and the part 148 causes the pin 80 to move the farthest away from the stud, and this causes the semi-circular end of the eyelet to be made. The part 149 causes the pin 80 to move near to the stud, and this causes the completion of the eyelet. The pin is then held in position by the part 100 until the vibrating of the work clamp down the other side of the slit completes the button-hole by the pin going to its original position in the portion 145. This operation forms what is known by the trade as the eyelet or looped button-hole. It will be noted that the cam member 30 revolves an equal distance at each stroke of the needle, and if the cam 118 were attached directly to the cam member the cam 118 would move in a circle and would pile up too many stitches at the end and make a defective button-hole; but by having the cam move in an elliptical path this is obviated. Of course it is desirable to have the stitches a little closer at the back end than on the side, but not to the extent which would be produced if the circular movement were used.

By referring to the diagrammatic Figs. 36 and 37, it will be seen more clearly the advantages gained by the cam 118 moving in an elliptical path instead of the circular path. In these two views I have indicated by the dotted lines 150 the movement of the cam member 30 for every ten strokes

of the needle or for every ten stitches, and the point where each dotted line 150 touches the semi-circle 151 indicates where the cam 118 would be; for instance, after the first 5 ten stitches it would have moved from *a* to *b* and the second ten stitches from *b* to *c* and so on until after a hundred and twenty stitches it would be at *m* and the first half of the button-hole would be finished, and the 10 reverse movement would under the same conditions, while the cam 118 is completing the circle, complete the button-hole. The vertical lines 152 represent the forward movement of the cam 118 and the horizontal 15 lines 153 the work clamp, and the vertical lines 154 represent the forward movement of the work clamp. It will be noted that all of the lines 153 are exactly the same length in both figures, and when the cam 20 moves from *a* to *b* ten stitches are crowded into the space between *n* and *o*, and when it moves from *b* to *c* ten are made in the space from *o* to *p*, and so on, and as the cam 118 moves from *a* to *g* each of the 25 spaces 155 from *n* to *t* increases in length and thus it will be seen that entirely too many stitches are crowded into the space from *n* to *o* and *o* to *p*, while from *p* to *q* the stitches would be normal and *q* to *r* 30 would not have sufficient stitches, and *r* to *s* and *s* to *t* entirely too few, and the exact reverse condition would exist while the cam 118 is moving from *g* to *m* and the clamp from *t* to *z*. Thus it will be seen that the 35 circular movement gives a very uneven stitching of the button-hole, by piling up too many stitches at the back end and entirely too few at the eyelet end, as the distance of travel or space is greatly increased 40 by the curvature of the eyelet. It will be noted that the work clamp needs to be retarded at the eyelet end in order to allow more stitches to be made while the eyelet is being formed, and I accomplish this by 45 having the cam 118 move in an elliptical path and by having the minor axis of the ellipse to the rear of the center of the stud 20, as will be seen by referring to Figs. 3, 19 and 37. It will be noted that the cam 50 118 follows an elliptical path, indicated by the line 156, and when the cam member moves from *a* to *b* the cam 118 moves from *a* to *b'*, and when the cam member has moved to *c* the cam has moved to *c'*, 55 and so on, and the clamp has moved from *n'* to *o'* while the cam member has moved from *a* to *b* and the cam from *a* to *b'*, and so on. It will be noted that the spaces *n'*—*o'* are suitable for the back end and 60 the space *o'*—*p'* is almost normal and the spaces *p'*—*q'* and *q'*—*r'* are normal, and the spaces *r'*—*s'* to *y'*—*z'* are gradually shortened in order to compensate for the increased travel or lengthened space to be 65 stitched while the eyelet is being formed,

and the work clamp at this point is moving in a line forming a compound curve instead of a straight line, and the retarding of forward movement allows the sewing machine to supply sufficient stitches to make 70 the eyelet have the proper number of stitches to compare with the sides of the button-hole. It is understood that the formation of the other side of the button-hole is the exact reverse of the movements 75 shown in the diagrams and that the diagram in Fig. 37 shows the movement of the work clamp relative to the needle and the stud of the attachment, it being understood that the back end of the button-hole is the 80 beginning of the operation and also the ending of the operation and that the back end is made while the work clamp is moving forward from *n'* to *o'* and the sides from *o'* to *t'* and the eyelet end from 85 *t'* to *z'*, or in other words, in the operation of making the button-hole the work on the button-hole is always in the reverse direction to the movement of the work clamp. It will be understood that I have stated for 90 convenience of illustration that ten stitches are made between each of these divisions; but by regulating the screw 8 any number of stitches can be made between the divisions; and from the foregoing it will be 95 clearly seen that the elliptical movement places the stitches very evenly along the sides of the button-hole and does not overcrowd the ends too much, as the space between *n'* and *o'* is greater than between 100 *n* and *o*.

What I claim is:

1. In a button-hole stitching attachment, the combination of a base-plate, a carrier 105 slideable laterally, a cutter-block movable on the carrier, a work holder mounted to reciprocate relative to the carrier and also to move laterally, means for reciprocating the work-holder, means for vibrating the work-holder, a cutter blade carried by the work-holder to partake of its said movements, said work-holder being connected with said carrier and cutter-block to shift the carrier laterally on vibration of the work-holder, whereby to maintain the cutter-block parallel with the blade during said vibration of the work-holder. 115

2. In a button-hole stitching attachment, the combination of a base-plate, a carrier slideable laterally, a cutter-block pivoted on the carrier, a work-holder mounted to reciprocate relative to the carrier and also to move laterally, means for reciprocating the work-holder, means for vibrating the work-holder, a cutter blade carried by the work-holder to partake of its said movements, 120 said cutter-block on the carrier having a sliding connection with the work-holder whereby the carrier will be shifted laterally 125 as the work-holder is vibrated, and the cut- 130

ter-block will maintain its position in the longitudinal axis of the work-holder and remain parallel with the cutter blade.

3. In a button-hole stitching attachment,

- 5 the combination of a base-plate, a carrier slideable laterally, a cutter-block pivoted on the carrier, a work-holder mounted to reciprocate relative to the carrier and also to move laterally, means for reciprocating 10 the work-holder, means for vibrating the work-holder, a cutter blade carried by the work-holder to partake of its said movements, means for moving the cutter blade along the work-holder, said cutter-block on 15 the carrier having a sliding connection with the work-holder whereby the carrier will be shifted laterally as the work-holder is vibrated, and the cutter-block will maintain its position in the longitudinal axis of the 20 work-holder and remain parallel with the cutter blade during vibration of the work-holder and travel of the blade.

4. In a button-hole stitching attachment, the combination of a base-plate, a carrier

- 25 slideable laterally on the base-plate, a cutter-block pivoted on the carrier, said cutter-block having a T-shaped slot, a work-holder mounted on the base to reciprocate relative to the cutter-block and also movable laterally whereby to feed material to be engaged by a needle reciprocating in a fixed path at the slot of the cutter-block, a cutter blade mounted on the work-holder and movable along the work-holder, to be engaged 30 by the needle bar and forced through the material in the work-holder and to co-operate with one edge of said block slot, said cutter-block having a slideable engagement with the work-holder whereby the vibration 35 of the work-holder will cause lateral movement of the carrier and also a swinging movement of the block on the carrier to maintain said cutting edge of the block parallel with the cutter blade.

45 5. In an attachment of the character stated, the combination of stitching mechanism including a needle, a work clamp, means for reciprocating and vibrating the work clamp, a knife carried by the work

- 50 clamp for cutting a buttonhole in advance of the stitching, a knife shield terminating in an upper stripper plate mounted on the work clamp, and means for preventing the knife shield from reciprocating with the work clamp but permitting it to vibrate with the clamp relative to the needle, a lower stripper plate having a substantially T-shaped slot therein, means for maintaining a portion of said slot in alignment with said

55 60 65 knife whereby a shearing cut may be effected, a spring member for supporting the knife which spring member has a yoke formed in the end thereof having a cam face and a rotary cam for co-operative engagement with said cam face.

6. In an attachment of the character stated, the combination of a base plate, a work clamp, a work plate operable by said work clamp in a lateral manner with respect to the base plate, a stripper plate pivoted to said work plate and having a substantially T-shaped slot therein, a cutting device operable through said slot and means for maintaining a portion of said slot in alignment with the cutting device whereby a shearing cut may be effected. 70 75

7. In an attachment of the character stated, the combination of a base plate, a work clamp, a work plate operable by said work clamp in a lateral manner with respect to the base plate, a stripper plate pivoted to said work plate and having a substantially T-shaped slot therein, a needle bar, a cutting device carried by the work clamp and operable through said slot, said cutting device being disposed in the path of travel of said needle bar and means for maintaining a portion of said slot in alignment with the cutting device whereby a shearing cut may be effected. 80 85 90

8. In an attachment of the character stated, the combination of a base plate, a work clamp, a work plate operable by the work clamp in a lateral manner with respect to the base plate, a stripper plate pivoted to the work plate and having a substantially T-shaped slot therein, a needle bar, a cutting device carried by the work clamp and operable through said slot, said cutting device being disposed in the path of travel of the needle bar, means for maintaining a portion of said slot in alignment with the cutting device whereby a shearing cut may be effected and means for withdrawing the cutting device from the path of travel of the needle bar at predetermined periods. 95 100 105

9. In an attachment of the character stated, the combination of a base plate, a needle bar, a reciprocal work clamp, a knife carried by the work clamp and normally in the path of travel of the needle bar, a work plate operable by the work clamp in a lateral manner with respect to the base plate, a knife shield mounted upon the work plate and terminating in a stripper plate, a pivotal stripper plate having a substantially T-shaped slot therein for the passage of said knife therethrough, means for preventing the knife shield from reciprocating with the work clamp and means for maintaining said slot in alignment with the knife whereby a shearing cut may be effected. 110 115 120

10. In an attachment of the character stated, the combination of a work clamp afforded a reciprocal and vibratory movement, a needle bar, a spring member carried by the work clamp and having a yoke formed at one end thereof, a cam face formed in said yoke, a rotary cam co-operatively disposed with respect to the cam face, a knife 125 130

carried by said spring member and advanced at predetermined periods by said rotary cam in the path of travel of the needle bar and a spring carried by said yoke for withdrawing the knife from said path.

11. In an attachment of the character stated, the combination of a base plate, a work plate movable laterally with respect thereto and a stripper plate movable in an arc of a circle with respect to the work plate and having a substantially T-shaped slot therein.

12. An attachment as described in claim 11 characterized by a knife movable through said slot and means operative to maintain a portion of said slot in alignment with said knife whereby a cutting edge is always present in order that said knife may effect a shearing cut.

Signed at New York, in the county of New York and State of New York, this 31st day of December, A. D. 1919.

ALBERTUS B. MATTINGLY.
